George E. Fenster
INVENTOR

UNITED STATES PATENT OFFICE.

GEORGE E. FENTRESS, OF LOS ANGELES, CALIFORNIA.

BAND-WHEEL COUNTERWEIGHT.

Application filed June 24, 1927. Serial No. 201,153.

My invention relates to rotating counterbalances and particularly to balancing the weight of the pump rods and of a portion of the column of oil in pumping oil wells.

5 The object of my invention is to provide a counterbalance which can be quickly put into and out of service without lifting heavy weights and which, when not in use, hangs idle on a rotating shaft.

10 A further object of my invention is to provide a counterbalance which does not need to be bolted to the band-wheel and which is entirely self-contained.

In pumping oil wells the pump rods and 15 plunger are suspended from one end of a walking-beam, to the other end of which is attached an assembly consisting of a pitman or connecting rod, a crank, and a shaft revolved by means of a band-wheel driven 20 by a suitable engine or motor.

The weight of the rods and of the column 25 of oil lifted by the pump is a very heavy load on the up-stroke and it is customary to counterbalance a portion of this weight, thus to some extent equalizing the load on the prime mover through the revolution of the crank.

This counterbalance is sometimes applied 30 as a dead weight on the crank end of the walking beam or an extension thereof, or sometimes by bolting weights to the side of the band-wheel lying next the crank. It is advantageous to apply the counterweight to a rotating rather than to a reciprocating 35 member, but application direct to the band-wheel is undesirable inasmuch as neither this structure nor the keys by which it is retained on the shaft are of sufficient strength to withstand the high stresses set 40 up by the change in direction of movement of the weights. Again, the weights required are very heavy and moving and bolting them into place is a laborious job which must be performed each time the well 45 is taken off the pump, as for pulling rods or tubing.

To overcome these disadvantages while retaining the desirable features of a rotating counterweight I suspend the weight 50 from the shaft in such manner that it may hang free and motionless on the rotating shaft while pulling the well and may be locked so as to revolve with the shaft while pumping, with the expenditure of a minimum of time and labor.

A preferred embodiment of my invention

is illustrated in the attached drawings, in which

Fig. 1 shows the band-wheel, the crank shaft and the calf-wheel clutch-sprocket 60 jack-post-bearing of a drilling rig in elevation, and a cross-section through my improved counterweight in place on the shaft.

Fig. 2 is a side elevation of my improved counterweight approximately on the line 65 2-2 of Fig. 1.

Fig. 3 is a plan view of one of the adjusting weights 25 indicated in Fig. 2.

Referring to Figs 1 and 2-1 is the band-wheel shaft with the band-wheel 2 mounted 70 thereon. The shaft extends through the jack-post bearing-box 3 to permit the calf-wheel clutch-sprocket, not shown, to be secured on the broken projection 4. Intermediate the band-wheel and the bearing-box 75 3 is a cylindrical collar 5, bored to a press fit on the shaft, and secured thereon by a plurality of heavy keys as at 6. As indicated in the drawing, this collar should be of materially greater diameter than the shaft, to 80 enable the collar to be firmly keyed to the shaft and to give clearance over the shaft for the removal of taper pins 9.

Surrounding this collar is a bearing-box 85 split into the halves 7 and 8, bored to a running fit on the collar which is thus permitted to rotate within the bearing-box while pulling rods or tubing. When pumping, the collar is prevented from rotating inside bearing 7-8 by inserting the taper pins 9 into 90 corresponding bores formed partly in the collar and partly in the bearing, and drawing them tight with the nuts 10. These pins act as keys, causing the bearing and the weight which is attached to it to rotate with 95 and around the shaft.

The operation of putting the counterweight out of commission thus resolves itself to dropping the weight to its lowest position, to relieve the strain on the pins, backing off the nuts and driving out the pins. The weight then hangs suspended on the collar 5 which revolves freely within the bearing 7-8. The weight is put into use by revolving the shaft until the halves of the 100 pinholes register, inserting the keys and drawing them up with the nuts. Either operation may be performed by one man in a few minutes without any other tool than a spanner and a hammer.

The ends of the bearing halves 7 and 8 are 105 extended to form the lugs 11 and 12, which

are faced to a close fit at 13 when the halves are adjusted to running fit on the collar 5. The tapered holes 33 are bored through the assembled bearing. The rods 14 have square 5 heads as at 21, a taper at the opposite end to fit the holes 33, and a threaded projection fitting the nuts 17, and for substantially the remainder of their length are threaded to fit the nuts 24. These rods fit snugly in the 10 round holes 20 through the main weight 19, the square heads being let into square cored holes in this weight. These rods are preferably provided with the square shoulder 18 against which lugs 11 and 12 may be tightly 15 drawn by the nuts 17. The rods 14 should be large and stiff, in proportion to the weight to be carried.

The adjusting weights 25 shown in Figs. 2 and 3 may be of any desired thickness, and 20 are preferably of the same plan shape as the inner plane surface of the weight 19. They are formed with a lug 28 which is one-half the thickness of the body of the weight, this lug being drilled through at 29 to fit loosely 25 over the stud 26 which is threaded into the weight 19 at the central point on its inner face. These lugs may have the rounded end indicated at 28, and a slot as at 31, this slot being of a width to slip readily over rod 14. 30 The center spacing of slot 31 from hole 29 is the same as from rod 14 to stud 26.

These adjusting weights may be added as required to the main weight 19 by removing nut 27 and backing up nuts 24, slipping one 35 or more pairs of weights, with lugs overlapped, over the stud 26, swinging the weights until the slots surround the rods 14, and tightening nuts 27 and 24.

The flange 32 formed on the upper half 7 40 of the bearing box 7-8 is to retain this box

against end movement on the collar 5 when the pins 9 are removed.

While I have described a complete embodiment of my invention I do not wish to be limited to the particular construction 45 shown, my invention being in fact limited solely by the attached claims.

I claim as my invention:

1. A counterweight for use on a rotatable shaft, comprising: a journal surrounding said shaft and firmly keyed thereto; a split bearing box fitted to revolve on said journal; lugs projecting from each half of said box and rods depending therefrom, the upper end of each said rod being shouldered, tapered and threaded to pass through one of said lugs; threaded nuts on said upper ends to hold said box in rotatable contact with said shaft when said nuts are drawn tight; a weight rigidly attached to the lower ends 60 of said rods, and a plurality of readily removable taper pins fitted transversely between said box and said journal and adapted to prevent rotation of said journal within said box. 65

2. A counterweight for use on a rotatable shaft, comprising: a journal of diameter materially greater than that of the shaft, firmly affixed to said shaft; a bearing box surrounding said journal and freely rotatable thereon; readily removable taper pins fitted between said journal and said box and adapted to prevent relative movement therebetween, and a weight depending from and rigidly attached to said bearing box. 75

In witness that I claim the foregoing I have hereunto subscribed my name this 15th day of June, 1927.

GEORGE E. FENTRESS.
